DESIGN FOR A BOTTLE

Jesse H. Newport, Jr., Upper Darby, Pa., assignor to Victor Metal Products Corporation, Brooklyn, N. Y., a corporation of New York

Application June 16, 1945, Serial No. 120,155

Term of patent 14 years

(Cl. D58—8)

To all whom it may concern:

Be it known that I, Jesse H. Newport, Jr., a citizen of the United States, residing at Upper Darby, in the county of Delaware and State of Pennsylvania, have invented a new, original, and ornamental Design for a Bottle, of which the following is a specification, reference being had to the accompanying drawing, forming part thereof.

Fig. 1 is a top plan view of a bottle, showing my new design.

Fig. 2 is a front view of the same.

I claim:

The ornamental design for a bottle, substantially as shown.

JESSE H. NEWPORT, JR.
